S. M. STOUGH & H. C. LARICK.

PIPE THREADING MACHINE.

APPLICATION FILED DEO. 27, 1911.

1,035,491.

Patented Aug. 13, 1912.

UNITED STATES PATENT OFFICE.

SAMUEL M. STOUGH AND HARRY C. LARICK, OF FRANKFORT, INDIANA.

PIPE-THREADING MACHINE.

1,035,491.

Specification of Letters Patent. Patented Aug. 13, 1912.

Application filed December 27, 1911. Serial No. 668,041.

To all whom it may concern:

Be it known that we, SAMUEL M. STOUGH and HARRY C. LARICK, citizens of the United States, residing at Frankfort, in the county 5 of Clinton and State of Indiana, have invented certain new and useful Improvements in Pipe-THREADING Machines, of which the following is a specification.

This invention relates to expanding dies 10 for cutting tapered threads upon pipes and has for the principal object to provide an elongated sliding eccentric for each die of a revoluble head having a tapered bore, the eccentric having a curved outer face of considerable length and slightly beveled to conform to the bore of the head, this construction presenting a wear surface of considerable area between the parts so that scouring 15 of the head, as in ordinary devices where the dies themselves bear against the head, is positively obviated.

A further object of the invention is to provide novel means for simultaneously adjusting all of the dies in position for cutting 20 threads on various sizes of pipes.

With the above mentioned objects in view the invention consists of certain novel details of construction and combination of parts hereinafter fully described and 25 claimed, it being understood that various modifications may be made in the minor details of construction within the scope of the appended claims.

In the accompanying drawings forming 30 part of this specification:—Figure 1 is a front elevation of our improved device. Fig. 2 is a side elevation of the device with parts in section. Fig. 3 is a fragmentary sectional view taken on the line 3—3 Fig. 1. Fig. 4 35 is a fragmentary sectional view taken on the line 4—4 Fig. 1. Fig. 5 is a detail perspective view of an eccentric with the related die attached.

Referring now to the drawings in which 40 like characters of reference designate similar parts, 10 designates a pipe upon which a tapered thread is to be cut, which pipe passes through and is secured to the work holder 11 by means of set screws 12, the work holder 11 is of a hollow substantially cylindrical shape and is interiorly threaded to receive the exteriorly threaded end of a hollow cylindrical body 13 which terminates remote from its threaded end in a peripheral flange 14.

A cylindrical head 15 encircles and projects between the flange 14 and is provided with a flange 16 which bears against the flange 14 and which terminates in a nipple 17 that surrounds the body 13 and is 60 revolubly mounted thereupon. For rotating the head, a ring 18 is snugly fitted upon the nipple and is provided with handle sockets 19, a set screw 20 being engaged through the ring and binding against the nipple. 65 The bore 21 of the revoluble head is tapered from the inner end toward the outer end, that is, is of less diameter at the outer end than at the inner end.

The body 13 is internally threaded to receive a substantially cylindrical hollow die carrier 22, the die carrier being provided near the outer end with a peripheral flange 23 having outwardly projecting tongues 24 on the edge which engage in notches 25 70 formed in the bore of the head and secure the die carrier against rotation in the latter, the die carrier being movable longitudinally in the body 13 by virtue of the screw thread connection therewith, during rotation of the head.

A plurality of dies 26, preferably four in number, are seated in recesses 27 formed in the outer edge of the die carrier, these dies being adapted for sliding movement 85 on the outer face of the die carrier flange 23, there being guide lugs 28 seated on said flange on opposite sides of each die to direct the sliding movements thereof. Each die is provided on the upper outer corner 90 with a downwardly opening hook 29.

Slidably fitted on the outer face of the die carrier flange 23 is a plurality of eccentrics 30, one for each die, each eccentric being provided with a curved outer edge 31 which bears throughout its length upon the inner wall of the revoluble head and is beveled to conform to the taper of the wall. The eccentric is furthermore provided with a curved inner edge of less radius of curvature than the outer edge so that both edges meet in a point as shown at 32, there being an upstanding rib 33 formed on said curved inner edge to fit in the downwardly opening hook of the related die.

By referring to Fig. 1 it will be noted that the eccentrics are of such length that their confronting terminals contact, this great length of the eccentrics presenting wear surfaces of considerable area to the 110

inner wall of the head so that as the eccentrics are moved radially by the dies as the die carrier advances in the body during the thread cutting operation, there will be no tendency for the inner wall of the head to be scoured or mutilated as invariably happens when the dies themselves bear upon the wall as in ordinary devices of this character. Furthermore, it will be noted that the eccentrics perform a two-fold function. Located as they are between the butt ends of the dies and the tapered wall of the head and being slidably connected to the dies, they not only control the recession of the dies in coöperation with the tapered wall of the head during the rotation of the latter, but are also adapted to be rotated or shifted to adjust the dies radially relative to the pipe being threaded.

For retaining the eccentrics and dies in place, and for simultaneously moving the eccentrics so as to adjust the dies to cutting position on various sizes of pipes, we provide a slide ring 34 which bears upon the outer faces of the eccentrics and dies and is held in this position through the instrumentality of a cylindrical nut 35 having a flange 36 which bears upon the outer face of the ring, the nut being threaded on to the outer end of the chuck as shown at 37. The slide ring is provided on the inner face with lugs 38 which bear against the butt ends of the eccentrics, and serve to rotate the latter counter-clockwise during counter-clockwise rotation of the slide ring, and furthermore the latter is provided in the edges with slots 39 which receive pins 40 carried by the eccentrics, this connection between the parts serving to rotate the eccentrics clock-wise during a clockwise rotation of the slide ring. Grips 41 are arranged on the outer face of the slide ring for manipulating the same.

What is claimed, is:—

1. A thread cutting tool including a head having a tapered bore, a radially movable die in said bore, means for moving said die longitudinally of said bore, and an elongated radially movable eccentric slidably connected to said die and having a curved outer edge bearing upon the wall of said bore.
2. A thread cutting tool including a head having a tapered bore, a radially movable die in said bore, means for moving said die longitudinally of said bore, and a radially movable eccentric having an outer curved edge conforming to the wall of said bore, and having an inner curved edge eccentrically disposed to said outer edge and slidably connected to said die.
3. A thread cutting tool including a head having a tapered bore, a radially disposed radially movable die in said bore, means for moving said die longitudinally of said bore,

a radially movable eccentric engaged transversely across the outer end of said die and having an outer curved edge bearing upon the wall of said bore, and having an inner curved edge eccentrically disposed to said outer edge, and a rib on said inner edge engaging the outer end of said die and slidably attaching the die to said eccentric.

4. A screw thread cutting tool including a head having a tapered bore, a plurality of radially movable dies in said bore, means carrying said dies and serving to move the dies longitudinally of said bore, radially movable eccentrics disposed transversely across the outer ends of said dies, each eccentric having an outer curved edge bearing upon the wall of said bore and having an inner curved edge eccentrically disposed to said outer edge and equipped with means for securing the related die for sliding movement thereupon, and means for simultaneously rotating said eccentrics about the axis of said bore whereby to adjust said dies.

5. A thread cutting tool including a stationary body, a revoluble head thereon having a tapered bore, a die carrier movable longitudinally through said body and secured for simultaneous rotation with said head, a radially movable die carried by said die carrier, and an elongated radially movable eccentric having a curved outer edge bearing upon the wall of said bore, and having a curved inner edge disposed eccentrically to said outer edge and having a projection interfitting with the outer end of said die and serving to slidably attach the die to the eccentric.

6. A die cutting tool including a stationary body, a revoluble head thereon having a tapered bore, a die carrier movable longitudinally through said body and having a flange non-rotatably and slidably connected to the walls of said bore, a plurality of radially disposed dies slidably fitted on said flange, elongated radially movable eccentrics on said flange each having an outer curved edge conforming to the contour of the wall of said bore, and having an inner curved rib eccentrically disposed to said outer edge and slidably securing the related die, and a slide ring retaining said eccentrics and said dies on said flange and having means for simultaneously rotating said eccentrics about the axis of said bore.

7. In a pipe threading machine, the combination with a holder for the pipe, of a head rotating relative thereto and provided with a bore, a die carrier movable in the head, a plurality of dies movably mounted in the carrier, and a series of independent segmental members slidably engaging said dies and adapted to be rotated to adjust the dies relative to the pipe and designed to move longitudinally with the carrier and to

bear against the wall of the bore of the head responsive to the thrust of the dies whereby the recession of the dies is controlled.

8. In a pipe threading machine, the combination with a holder for the pipe, of a head rotating relative thereto and provided with a bore, a die carrier movable longitudinally of the head, a die movably mounted in the carrier, and an element movably connected to the die and adapted to be rotated to adjust the latter radially relative to the pipe being cut, and designed to move longitudinally with the carrier and to bear against the wall of the bore of the head responsive to the thrust of the die whereby the recession of the die in its longitudinal movement is controlled.

9. In a pipe threading machine, the combination with a holder for the pipe, of a rotary head having a tapered bore, a plurality of radially disposed and radially movable dies mounted in the carrier, and an eccentric segmental member for each die, said members being arranged end to end and normally bearing against the wall of the bore of the head responsive to the end thrust of

the dies while at work whereby the recession of the dies is controlled, said segmental members being adapted to be rotatably shifted to adjust the dies radially. 30

10. In a pipe threading machine, the combination with a support for the pipe, of a rotatable head having a tapered bore, a radially movable die, means for moving the die longitudinally of the bore and an element slidably connected to the die at its inner edge, the outer edge of said element bearing against the wall of the bore thus controlling the recession of the die when the latter is moved longitudinally, and means 35 for shifting the element to radially adjust the die. 40

In testimony whereof we affix our signatures, in the presence of witnesses.
